CLAIM

We claim the ornamental design for a intraosseous needle and stylet, as shown and described.

DESCRIPTION

FIG. 1 is a front, left perspective view of an intraosseous needle and stylet;

FIG. 2 is a front, right exploded perspective view of the claimed design of FIG. 1;

FIG. 3 is a front elevation view of the claimed design of FIG. 1;

FIG. 4 is a rear elevation view of the claimed design of FIG. 1;

FIG. 5 is a right side view of the claimed design of FIG. 1; FIG. 6 is a left side view of the claimed design of FIG. 1; FIG. 7 is a top view of the claimed design of FIG. 1; and, FIG. 8 is a bottom view of the claimed design of FIG. 1. The broken lines shown in FIGS. 1 and 2 illustrate portions of the intraosseous needle and stylet that form no part of the claimed design.

1 Claim, 5 Drawing Sheets
